UNITED STATES PATENT OFFICE.

HENRY ATWATER, OF CHATTANOOGA, TENNESSEE.

SASH-FASTENER.

No. 901,771.

Specification of Letters Patent.

Patented Oct. 20, 1908.

Application filed July 17, 1908. Serial No. 444,110.

To all whom it may concern:

Be it known that I, HENRY ATWATER, a citizen of the United States, and a resident of Chattanooga, in the county of Hamilton 5 and State of Tennessee, have invented a new and Improved Sash-Fastener, of which the following is a full, clear, and exact description.

The improvement is of a class in which a 10 fastener is mounted upon the meeting rail of the lower sash, and by adjustment locks both sashes in closed condition.

The purpose of my invention is to provide 15 novel, simple details of construction for a device of the character indicated, which afford a neat, strong, conveniently-operated sash fastener, which affords means for locking both sashes closed, or either sash opened more or less as may be desired.

20 The invention consists in the novel construction and combination of parts, as is hereinafter described and defined in the appended claims.

Reference is to be had to the accompanying 25 drawings forming a part of this specification, in which similar characters of reference indicate corresponding parts in all the views.

Figure 1 is an inner side view of an upper and lower sash at their meeting transverse 30 rails, a portion of the window casement being broken away, and the improved sash fastener secured on the top of the meeting rail of the lower sash and bearing upon a side bar of the upper sash; Fig. 2 is a transverse sectional view of the sashes and a face view of 35 the sash fastener, seen in the direction of the arrow x in Fig. 1, and showing the sash fastener in unlocked condition; and Fig. 3 is a sectional view on the line 3—3 in Fig. 1, seen 40 in the direction of the arrow x' , and showing the fastener device adjusted for securing both sashes in closed condition.

In the drawings, A indicates a window casement, and A' a molding strip of said casement at the right hand side thereof.

B is the upper sash, and C the lower sash, both 45 slidable in the usual manner in the casement, having the adjacent surfaces of their side bars C', B', separated by a parting strip D.

The improved sash fastener primarily consists of a base plate 5, having an upright flange 5^a formed near a straight edge thereof, said flange in service facing the side stile of 50 the casement. An opening is formed horizontally in the side edge of the flange 5^a, and

is concaved at its bottom, as shown at a in Fig. 2, said opening affording a bearing for a journal b on a short shaft that carries at one end a fixed handle lever 6, and at the opposite end a cam block.

The cam block is formed with two cam surfaces d , d , that increase in distance from a common center in opposite directions, thus affording two similar cam sections 7, 7, and 65 as best shown in Fig. 3, the cam surfaces d are similarly serrated. The handle lever 6 projects across the face of one cam section 7, but is spaced therefrom sufficiently by the journal shaft b to permit said shaft to have a 70 loose engagement with the bearing a , so that the cam sections 7, 7, may be rocked freely by the manipulation of the handle lever.

The base plate 5 is extended somewhat beyond the upright flange 5^a, and upon said extension 5^b two similar ears e , e , are formed that project upward and are laterally apertured as at e' in Fig. 3.

Two similar clamping dogs 8, 8, are completing details of the improved sash fastener, 80 each consisting of a metal bar having flat sides that are parallel with each other and slightly curved edges. A transverse journal pin g is formed or secured on the lower end of each clamping dog 8, said pins having a rocking engagement with the respective ears e , 85 loosely occupying the transverse apertures e' therein. The relative position of the clamping dogs 8 is such with regard to the cam sections 7, that the inner edges of the dogs will 90 be opposed to the cam surfaces d . As shown clearly in Fig. 3, the inner edges of the clamping dogs 8 are slightly concave, and transverse serrations h are formed therein that correspond in form and size with the serrations 95 on the cam surfaces d . Upon the outer convex edges of the clamping dogs 8, transverse grooves are formed, thus producing ratchet teeth therein which hook upward.

The width of the upper cross bar or meeting rail C² of the lower sash C, permits the base plate 5 of the sash fastener to be mounted and secured thereon, so that the clamping dogs 8, 8, will respectively be positioned opposite the inner surface of the right 100 hand bar B' of the upper sash and the opposed surface of the molding strip A' on the casement A.

It will be noted that when the handle lever 6 is rocked into an upright position, as indicated by the arrow x' , in Fig. 2, and arrow x^2 in Fig. 3, the clamping dogs 8 will be free to

assume an upright position and have ample clearance from the side bar B' and molding strip A', so that either sash may be freely slid to open or close the window.

5 When it is desired to fasten the sashes B, C, in closed adjustment, as is indicated in Fig. 3, this is instantly effected by rocking the lever 6 downward, as shown by dotted lines in said figure, which will correspondingly rock the cam sections 7 and enforce their engagement with the concave edges of the clamping dogs 8. The pressure exerted by the cam sections 7 on the dogs 8 will force them outward simultaneously, and embed 15 their teeth in the adjacent surfaces of the side rail or bar B' and the casement molding strip A', thus producing a positive locking adjustment of the fastener device that can only be released by an elevation of the lever 6.

20 It will be seen that the improved sash fastener is adapted for securing the sashes B, C, in any desired position of open adjustment therefor, by means of the lever 6 and parts of the device controlled thereby; this 25 feature being particularly advantageous when it is desired for the purpose of ventilation to secure the upper sash lowered a few inches, or the lower sash raised slightly for a like purpose.

30 Having thus described my invention, I claim as new and desire to secure by Letters Patent:

1. A sash fastener, comprising a base plate having an upright flange that is provided 35 with a lateral opening, a handle lever, a double edged cam, a shaft connecting the lever and cam, and clamping dogs carried by the base plate and adapted to receive pressure from the cams.

40 2. A sash fastener, comprising a base plate, an upright flange thereon having a lateral opening therein, an extension of the base plate near said flange, perforated ears on the extension, a cam block formed in two sections, the cam surfaces thereon trending oppositely, a handle lever, a short shaft joining the cam blocks with the lever, said shaft engaging the opening in the upright flange, and 45 clamping dogs rockable on the perforated

ears, said dogs receiving pressure from the cam sections when they are rocked with the lever.

3. A sash fastener, comprising a base plate, an upright flange on said base plate near one straight edge thereof, said flange having a lateral opening therein that is concave in its bottom, forming a bearing, the base plate having an extension beyond the flange, upright ears on the extension, said ears each having a lateral opening therein, a cam block formed in two integral sections, the cam faces of which trend oppositely, said faces being serrated, a handle lever, a short shaft connecting the cam sections with the lever, said shaft having rockable engagement with the upright flange in its opening, and two clamping dogs each pivoted at one end on a respective ear, and having curved edges 60 that are serrated, the concave edges thereof having engagement with the serrated faces of 65 the cam sections.

4. The combination with a window casement, and an upper sash and a lower sash, both slideable in the casement, of a sash fastener, comprising a base plate securable on 75 the meeting rail of the lower sash, an upright flange on the base plate, having a lateral opening therein near its upper edge, a cam block formed in two sections, the cam surfaces of which trend oppositely, said surfaces 80 having serrations thereon, a handle lever, a short shaft connecting the cam block with the handle lever, said shaft loosely engaging within the opening in the upright flange, ears on the base plate, having lateral openings 85 therein, and clamping dogs pivoted to the ears through the openings therein, said dogs receiving pressure on their inner edges from the cam sections and pressing upon the upper sash and casement when the lever is rocked 90 downward.

In testimony whereof I have signed my name to this specification in the presence of two subscribing witnesses.

HENRY ATWATER.
